PAPER MACHINE AND METHOD OF
MAKING PAPERHarold O. Bing, Sandusky, Ohio, assignor to
Beloit Iron Works, Beloit, Wis., a corporation
of Wisconsin

Application October 29, 1931, Serial No. 571,732

12 Claims. (Cl. 92—39)

This invention relates to paper making machines of the cylinder type and includes a novel process of making paper.

More specifically this invention relates to a novel cylinder paper machine having means for removing water from the paper web during its formation without the aid of a battery of heavy duty presses and thereby producing a sheet of maximum strength per unit weight.

10 In cylinder type paper machines now on the market a cylinder mold or plurality of molds is immersed in a stock vat or plurality of vats. The cylinder mold is rotated in the vat and being of foraminous construction the white water of the paper stock tends to flow into the cylinder. The white water is removed from the center portion of the cylinder and the fibers of the stock remain on the surface of the cylinder mold in a somewhat matted condition. A pickup felt contacts 15 the cylinder near the top thereof and removes the matted fibers from the surface of the cylinder mold. A fibrous web is thus suspended on the under side of the belt. After leaving the last cylinder mold the pick up felt is entrained around a so-called strain roll. As the wet felt starts 20 back on its journey above the cylinder molds, the fibrous web no longer is suspended from its under side but is on its upper surface. After the wet felt passes over the strain roll it meets an upper 25 felt and the fibrous web on the pickup felt is gently squeezed between the two felts by means of suction and press rolls. The paper web is then removed from the felts and subjected to high 30 pressures by heavy duty presses to remove the 35 water therefrom.

Ordinarily the paper sheet is subjected to pressure from a minimum of six presses up to a maximum of about ten or twelve. Each time the sheet goes through a set of presses it is compacted, 40 making it weigh more per unit area. The heavy duty press rolls also distort the sheet which distortion when added to the stress that takes place on the sheet between each set of presses greatly reduces the strength of the final product.

45 During the last few years there has been a big demand to produce a cylinder made sheet of paper having less weight per unit area and having greater strength. After considerable experimentation I have found that the only practical 50 way to accomplish this result is to eliminate the large number of presses ordinarily used in the process of removing water from a cylinder formed sheet. I have also found that it is possible to 55 entirely do away with the top felt ordinarily used

in the cylinder type machine and still obtain excellent results.

It is therefore an object of this invention to provide a cylinder type of paper machine to produce a paper sheet having maximum strength per 5 unit weight.

It is a further object of this invention to provide a cylinder type of paper machine in which the paper web passes directly to water extracting means while still on the under side of the pickup 10 felt.

Another important object of my invention is to provide a cylinder type of paper machine in which the pressing operation is reduced to a minimum.

A specific object of this invention is to provide 15 a novel cylinder type of paper machine in which the customary top felt is eliminated and the fibrous web from the pickup felt is supported on a Fourdrinier wire during the water extracting operation.

Other and further objects of this invention will 20 become apparent as the description proceeds.

On the drawings:

Figure 1 is a diagrammatic side view of a cylinder type of paper machine according to this 25 invention in which the sheet passes through one or more extractor rolls while still on the pickup felt before passing to the first suction press. The suction press is provided with a wire in place of a felt, said wire being similar to the wire used on a 30 Fourdrinier machine. The sheet is subjected to very light pressures at the extractor rolls which remove sufficient water to prepare it for the heavy pressures applied at the first suction press. After 35 leaving the suction press the paper sheet is separated from the pickup felt and passes through one or more presses of either the suction or plain type and then onto the dryers.

Figure 2 discloses a diagrammatic side view of an alternative arrangement of the paper machine 40 according to this invention in which the partially formed sheet on the pickup felt first passes through a suction press while still on the felt, then through a series of light duty perforated presses, and then through a heavy duty suction press. A 45 wire similar to a Fourdrinier wire is entrained around the suction rolls and perforated extractor rolls to support the sheet. From the heavy duty suction press the sheet passes through one or more other presses of either the suction or plain 50 type and from thence onto the dryers.

Figure 3 discloses another diagrammatic side view of an alternative arrangement of paper machine according to this invention in which the partially formed paper sheet on the pickup felt 55

passes directly to a suction couch roll where a large amount of water is removed with light pressures. The sheet is there transferred onto a Fourdrinier wire by aid of the suction while the pickup felt returns to the cylinders. The sheet is then carried on the wire to another suction couch roll where it is subjected to high vacuum to remove more water, after which it is removed from the wire and passed onto one or more presses 5 of either the plain or suction type before entering the dryers. The second suction couch can be operated with or without a top press roll.

Figure 4 is a cross sectional view of one form of extractor roll for use in the paper machine which 15 consists of a perforated shell having perforations completely around its entire periphery. Only a few perforations are disclosed on the drawings however.

Figure 5 is a broken cross sectional view of an 20 alternative form of extractor roll which is equipped with a mesh wire around its periphery to allow the water to drain through into the interior of the drum.

As shown on the drawings:

25 In Figure 1 the reference numerals 1, 2, 3, 4, and 5 indicate pulp stock vats of the general type for supplying fibers to the rotatable cylinder molds 6, 7, 8, 9, and 10, respectively. A pickup felt 16 contacts between the cylinder molds 6, 7, 8, 9, and 10 and couch rolls 11, 12, 13, 14, and 15, thereby removing the fiber web from each of the cylinder molds and, as the pickup felt progresses, gradually building up a paper sheet on the under 30 side of the felt. Supporting rolls 17 and tension roll 18 guide the pickup felt through the cylinder machine. Motion may be imparted to the felt by suitable means, as by a set of driven press rolls. A whipper (not shown) may be provided to clean the pickup felt as it passes to and from roll 17a. A washing device may be inserted as 35 shown at 19 to wash the felt.

After leaving the last cylinder mold 10 the pickup felt and fibrous web suspended on its under side are passed between perforated extractor rolls 20, 21, 22, and rubber press rolls 23, 45 24, 25, where the sheet is subjected to light pressures. A considerable amount of water is removed from the fiber web at this stage, however, the water draining through the perforated rolls 50 20, 21, and 22.

After passing over the extractor rolls the fibrous web on the under side of the pickup felt is brought into contact with a Fourdrinier wire 55 30 to support the web. The wire 30 is entrained around guide rolls 31 and a suction press roll 32. As the fibrous web and pickup felt advance along the wire they are directed over the suction press roll 32 at which point the web is separated from the felt by the aid of the suction and more 60 water is removed therefrom. The felt is directed back to the cylinder around rubber strain roll 33 located above the suction roll. The fibrous web, now paper web 34, is sufficiently formed to support itself and is directed onto another Fourdrinier wire 40 entrained around guide rolls 41. While 65 on the wire it is passed between another suction press roll 42 and rubber top press roll 43. The Fourdrinier wire 40 is kept taut by means of a tension roll 47.

70 The paper web 34 is next directed over a guide roll 45 and onto another Fourdrinier wire 50 entrained about guide rolls 51. The paper web on the Fourdrinier wire 50 is then passed between another suction press roll 52 and a rubber top 75 press roll 53. From there the paper web may be

passed between heavy duty presses 62 and 63 and from thence onto the drying rolls 71, 72, and 73. While the rolls over the extractor and suction rolls preferably have a rubber surface such construction is not essential.

From the above description it will be seen that the use of an upper or top felt is entirely dispensed with and a large amount of water in the web on the pickup felt is removed before the web is subjected to pressure between heavy duty press rolls. 10 The customary battery of heavy duty press rolls is entirely dispensed with. If desired only one suction press roll may be used and in some cases more than the three suction press rolls disclosed may be used. For most purposes, however, it 15 has been found that the three suction rolls are sufficient to dry the paper enough so that it may pass between a heavy duty press roll without deformation or stretching. At the same time, however, a strong sheet of less density is produced since the fibres have not been unduly compacted during the water removal operation.

Figure 2 discloses a diagrammatical side view of a straight line cylinder type paper machine similar to that disclosed in Figure 1 but differing therefrom in that the pickup felt and fiber web on the under side thereof after leaving the last cylinder mold 10 are directed between a suction press roll 83 and a top press roll 84 on a Fourdrinier wire 80.

After passing between the suction roll and the top press roll 84 the fiber web is next passed, while still between the pickup felt and the Fourdrinier wire 80, between a series of light duty presses consisting of hollow perforated rolls 85, 86, 87, 30 and 88 and upper light duty press rolls 89, 90, 91, 35 and 92.

Upon leaving the last extractor roll 88 and upper roll 92 the pickup felt, paper sheet and Fourdrinier wire are passed between a heavy duty suction press roll 101 and a strain roll 100. At this 40 point the paper web is sufficiently formed and dried to be separated from the pickup felt and the Fourdrinier wire 80. The pickup felt is directed back over the cylinder mold vats and the Fourdrinier wire 80 is directed back to suction roll 83 45 into cooperating relation with the pickup felt. The wire is entrained around suction rolls 83, 101, guide rolls 81 and tension roll 82. The paper web 34 after being separated from the pickup felt is directed successively onto other Fourdrinier wires 50 40 and 50, passed through other suction press rolls 42 and 52, then between heavy duty press rolls 62 and 63, and thence onto the dryers 71, 72, and 73 in the same manner as indicated in Figure 1.

From this arrangement in Figure 2 it will be seen that the fiber webs deposited on the pickup felt are immediately subjected to suction upon leaving the last cylinder mold, whereas the pickup felt and fiber web thereon in Figure 1 are first 60 directed through a series of extractor rolls before suction is applied to the wet fiber web. It is to be understood in the operation of a machine as disclosed in Figure 2 that the suction applied at the first suction roll 83 should not be great enough to 65 disrupt the wet fibers on the pickup felt. Only a very light pressure is maintained between suction press 83 and the roll 84.

In Figure 3 another alternative construction of my novel cylinder machine is disclosed in which 70 the fiber web is separated from the pickup felt immediately after leaving the last vat 5 and cylinder mold 10. In this arrangement the pickup felt and web on the under side of the felt are passed between a suction couch roll 120 and strain 75

roll 121. At this point the pickup felt is directed around the strain roll 121 back above the cylinder vats while the fibrous web is contacted with a Fourdrinier wire 122. The wire is entrained 5 around guide rolls 123 and suction couch rolls 120 and 124. The fiber web after passing between the first suction couch roll 120 under light pressure is directed, while on the Fourdrinier wire 122, over 10 the second suction couch roll 124 under high vacuum. Roll 124 is not provided with an upper press roll. After passing over this second suction couch roll 124 the web is sufficiently dry to support itself and the resulting web 34 is then directed onto another Fourdrinier wire 40 and carried between the suction press roll 42 and top press roll 15 43. After leaving the Fourdrinier wire 40 the web 34 is carried over to another Fourdrinier wire 59 and between suction press roll 52 and top press roll 53 thence between heavy duty press rolls 62 20 and 63 and then onto the dryers 71, 72, and 73 in the same manner as indicated in Figures 1 25 and 2.

Figures 4 and 5 disclose cross sectional views of two types of extractor rolls used in my novel type 30 of cylinder machine disclosed in Figures 1 and 2. Figure 4 discloses a roll which consists of a metallic shell 130 provided with perforations 131 around its entire periphery. The figure in the drawings discloses only a few of these perforations. This roll is a hollow shell made of a metal, 35 such as for example brass or bronze.

Figure 5 discloses an alternative arrangement of extractor roll which is made up of supporting spiders 140, formed integrally with hub members 35 141 and having rim portions 142. A heavy coarse mesh wire 143 is secured around the periphery of the rims 142 and forms a support for a finer wire of the Fourdrinier type 144. Wire 144 forms the outer surface of the roll. Spiders and rims 40 such as 140 and 142 may be spaced throughout the length of the roll to adequately support the wire 143. If desired spider supporting members 45 may be used at the ends of the rolls only and rigid metallic rods stretched across the roll at spaced intervals around the periphery to support the wire.

In each of the cylinder machines described in Figures 1, 2, and 3 it will be noted that the conventional top felt is eliminated and the sheet is 50 subjected to very light pressures in a limited number of operations. This greatly increases the bulk of the sheet as well as its strength per unit of weight. The product of such a machine is therefore of maximum strength per unit weight. 55 The run of the sheet through the machine is straight through the molds and directly into the press section. In other words the sheet moves always forward through the molds, the extractor rolls, the presses and the dryer section and is not 60 reversed as in the case of the conventional type of cylinder machine, where the pickup felt carrying the wet web on the under side thereof is passed between press rolls to remove water from 65 the web. This straight line arrangement permits the machine to be run at greater speeds and results in a saving in equipment cost.

The combination of suction rolls and extractor 70 rolls, according to my invention, produces a new result not only in the quality of the paper sheet produced but also in the economy of operation. By my novel arrangement of extractor rolls, suction press rolls and suction couch rolls I am able 75 to dispense with the large number of press rolls

heretofore necessary in cylinder type machines. Bringing the sheet in contact between extractor rolls and between the Fourdrinier wire and the pickup felt and subjecting the sheet to both mechanical as well as atmospheric pressure accomplishes results never before known in the paper art and provides a speed and ease of operation heretofore considered impossible in cylinder type paper machines.

5

I am aware that many changes may be made 10 and numerous details of construction may be varied through a wide range without departing from the principles of this invention, and I, therefore, do not purpose limiting the patent granted hereon otherwise than necessitated by 15 the prior art.

I claim as my invention:

1. In a cylinder type of paper machine including a plurality of cylinder molds and a pickup 20 felt to build up a composite fibrous web, extractor rolls for receiving the fibrous web to remove water therefrom, foraminous carriers to support said web, suction rolls to extract further quantities of water from said web and aid in transferring the web from said pickup felt to one of 25 said carriers, additional suction press rolls to further dry and form said web while supported on a foraminous carrier, heavy duty press rolls for receiving said web from said suction press rolls and 30 drying rolls to completely dry said web.

30

2. In a cylinder type of paper machine the combination of a plurality of web forming molds and a pickup felt for receiving and transferring the composite web so formed, a foraminous carrier for receiving the composite web directly from 35 said pickup felt, a primary suction roll located immediately after the last web forming mold to remove water from the web, extractor rolls located after said primary suction roll to remove further quantities of water, a secondary suction 40 roll to remove more water from the web and separate the web from the pickup felt, a secondary foraminous carrier for receiving the separated web and additional suction means to further dry 45 said web.

45

3. In a cylinder type of paper machine including a plurality of web forming molds and a pickup 50 felt for receiving and transferring the composite web so formed, a foraminous carrier for receiving the composite web directly from said pickup felt, a primary suction roll to remove water from said web and effect the transfer of the web from the pickup felt, a secondary suction roll to remove further quantities of water from the web while still on said foraminous carrier, a secondary 55 foraminous carrier to carry said web over additional suction rolls to extract further quantities of water from said web, heavy duty press rolls for receiving said web only after it is thoroughly formed so as to prevent distortion 60 thereof and heated drying rolls to remove the last traces of water from the web.

55

4. The method of making paper which comprises building up a composite web of fibrous material on a pickup felt, subjecting said fibrous web 65 to a light suction to gently remove water therefrom while said web is still carried by said pickup felt, transferring said web by means of suction to a foraminous wire, extracting further quantities of water by gradually increasing suction operating through the wire and subjecting the web alone to heavy pressure to remove further quantities of water therefrom after the web is sufficiently formed to resist distorting and crushing under the heavy pressure.

75

5. The method of making paper which comprises building up a composite web of fibrous material on a pickup felt, subjecting said fibrous web and pickup felt to the action of extractor rolls to gently extract water therefrom, transferring said web to a foraminous wire and extracting further quantities of water from said web by means of suction applied through the wire, said suction being applied in gradually increasing amounts so as not to disrupt the fibrous structure of the web.

6. In the manufacture of paper on a cylinder type of paper machine the process of removing water from the wet web of paper by gentle extraction between extractor rolls followed by a gradually increasing suction treatment to produce a well-formed sheet before subjecting the sheet to heavy pressures.

7. In a cylinder type of paper machine including a plurality of cylinder molds and a pickup felt for receiving a web of paper thereon, the combination of a foraminous carrier belt entrained around suction rolls for receiving the pickup felt and fibrous web thereon to extract water therefrom and a plurality of water extracting rolls positioned between said suction rolls along the upper run of said foraminous wire.

8. The method of making paper of maximum strength per unit weight which comprises forming a composite web of fibrous material on a pickup felt, gently removing water from said web by means of extractor rolls, supporting the partially dried web on a foraminous carrier and subjecting the web on the carrier to increasing suction treatment to produce a well formed sheet before subjecting the sheet to heavy pressures.

9. In the manufacture of paper on a cylinder type of paper machine, the process of removing water from the wet web of paper formed on said machine without distorting said web which comprises gently extracting water from the web by means of light duty extractor rolls, supporting the web on a foraminous carrier belt, applying suction through the carrier belt to remove further quantities of water, transferring the web to additional

foraminous carrier belts, subjecting the web on each succeeding carrier belt to an increased suction treatment and when the web is substantially dry allowing it to proceed to the press and dryer rolls.

10. In a cylinder type of paper machine including a plurality of web forming molds and a pickup felt for receiving and transferring the composite web so formed, a foraminous carrier for receiving the composite web directly from said pickup felt, suction means for effecting the transfer from said pickup felt to said carrier, said suction means also aiding in the removal of water from said composite web, screen faced extractor rolls below the upper run of said carrier and top press rolls above said extractor rolls to press the web and carrier thereagainst for the removal of water therefrom.

11. In a paper machine of the cylinder type, the combination of a fibrous web forming part, a pickup felt for receiving the fibrous web on the under side thereof, a foraminous carrier positioned after said forming part for receiving the fibrous web, means comprising a suction roll to transfer said fibrous web from said felt to the foraminous carrier, screen faced extractor rolls below the upper run of said carrier and top press rolls above said extractor rolls to press the web and carrier thereagainst for the removal of water therefrom without distorting and crushing the web.

12. In a paper machine of the cylinder type, the combination of a fibrous web forming part, a pickup felt for receiving the fibrous web on the under side thereof, a foraminous carrier positioned after said forming part for receiving the fibrous web directly from the pickup felt, a foraminous metallic roll below the upper run of said foraminous carrier and a top rubber press roll cooperating therewith for pressing the web on the carrier against the foraminous roll for the removal of water therefrom.

HAROLD O. BING.
